UNITED STATES PATENT OFFICE.

ARTHUR PEMBERTON WOOD, OF HALE, ENGLAND.

APPARATUS FOR ELECTRICALLY OPERATING AND CONTROLLING PLANING-MACHINES AND THE LIKE RECIPROCATING TOOLS.

1,147,666.

Specification of Letters Patent. Patented July 20, 1915.

Application filed August 19, 1912. Serial No. 715,874.

To all whom it may concern:

Be it known that I, ARTHUR PEMBERTON Wood, a subject of the King of Great Britain, and residing in Hale, in the county of 5 Chester, England, have invented certain new and useful Improvements in Apparatus for Electrically Operating and Controlling Planing-Machines and the like Reciprocating Tools, of which the following is a specification.

This invention relates to apparatus for electrically operating and controlling planing machines and the like reciprocating tools, and has reference more particularly to 15 that type of planing machine or reciprocating tool in which there are two feed-screws, or two sets of feed-screws or the like traversing devices; which may alternatively be used respectively for making the working, 20 that is to say, the cutting stroke, or for traversing the tool across the work at the end of each cut, the arrangement being such that when the one device is used to make the working stroke the other is used to give the 25 necessary traverse. In such machines, as at present constructed, and when electrically operated, the electro-motor is so geared to the machine that it is adapted to operate either one or other of the feed-screws, the 30 remaining feed screw being operated by the usual mechanical tappet motion; or in some cases two motors may be fitted, one to each feed-screw, in which case the feed-screw used for traversing is disconnected from its 35 motor and is operated by the usual mechanical tappet motion.

According to the present invention a reversing motor is fitted to each feed-screw or set of feed-screws, and the electrical arrangement is such that when the one motor is used to make the working stroke, the other motor is not disconnected from its feed-screw but is connected to a switch or switches operated by tappet gear actuated 45 by the reciprocating part, or by a part connected therewith, so that at the end of each stroke, a voltage is applied to it for a sufficiently long period to impart to it the necessary small angular movement to effect the 50 desired traverse or feed.

The invention is illustrated in the accompanying drawings which show, by way of example my invention applied to a horizontal and vertical planer, and in which;—

55 Figure 1 is a side view of the tool and

motors; Fig. 2 a corresponding end elevation; and Fig. 3 a diagram of the connections and the switch gear.

In the type of planer selected for illustration, the work to be planed is stationary, 60 and there are two sets of feed-screws, one set of two screws a, a , to give the tool holder B a horizontal movement, and one screw c to give it a vertical movement. I connect, preferably directly, a reversing electro-motor to 65 each of the feed-screws or set of feed-screws, and, in the latter case, mechanically gear the several feed-screws of a set together so as to insure synchronous movement. The motor A is connected to the two screws a, a , say 70 by means of the pairs of bevel wheels a^1 , connecting the motor spindle to a transverse shaft, and pairs of bevel wheels a^2 connecting this shaft to the respective screws a . The motor C is connected to the screw c by 75 the spur gearing a^1 .

The drawing shows a convenient mode of arranging the motors, but the positions of the motors and mode of connecting them to the planer will depend upon the type of tool. 80 The arrangement of the screws, slides S, tool carrier B, and main frame D are of the usual construction and need not be further described.

The switch gear and apparatus by which 85 a motor is connected to the supply mains when employed to reciprocate the tool will be termed the working motor operating gear, and the switch gear and apparatus by which a motor is connected to the supply 90 mains when employed to traverse a tool by the amount of the feed will be termed the traversing motor operating gear.

Any suitable known working motor operating gear may be employed, but preferably that described in the application for Letters Patent No. 580657 one modification of which is illustrated in Fig. 3. Any suitable traversing motor operating gear may be employed, but preferably that illustrated in Fig. 3. The two motors are connected to a change-over switch which when in one position connects the motor A to the working motor operating gear and connects the motor C to the traversing motor operating gear, and which when in the other position reverses these connections.

Referring now to Fig. 3, which is a diagram of the general arrangement of the switches and connections,—A is the motor 110

geared to the screws a , a , which it will be assumed are being used for giving a reciprocating motion to the tool carrier B. C is the motor geared to the screw c which under these circumstances will be used for feeding the tool across the work for successive cuts. As and Cs are, respectively, the shunt windings of the motors A and C, which windings are connected through suitable shunt regulators Ar and Cr to the supply mains or other suitable source of potential P. E is a change-over switch which is adapted to connect the armature of A to the mains F and the armature of C to the mains G, or, alternatively, the armature of A to the mains G and the armature of C to the mains F.

Under the conditions assumed, the blades e^1 and e^2 of the switch E connect the armature of the motor A to the mains F, and the blades e^3 and e^4 of this switch connect the armature of the motor C to the mains G. If the switch E be moved to the left the armature of the motor A will be connected by the blades e^5 and e^6 to the mains G and the armature of the motor C will be connected by the blades e^7 and e^8 to the mains F. The mains G are connected to a generator such as H having a constantly driven armature, and the switch T (which is adapted to be closed by the tappet gear t^1 , t^2 as shown in Fig. 1) may be employed to momentarily excite the shunt field of the said generator which then generates current and actuates the motor C, the degree of actuation being controlled by the regulation of a shunt resistance such as K. I prefer, however, to fit a device the function of which is to regulate and definitely determine the angular movement to be imparted to the motor C. I have shown such a device diagrammatically in Fig. 3.

Referring again to Fig. 3, the mains G are energized by the feed generator H designed to give a comparatively low voltage, and the armature of which may be mechanically coupled to the main generator, or to the motor driving the latter; the armature of H therefore runs continuously while the machine is in operation. H_s is the field winding of the feed generator H. The field winding H_s is connected through a reversing switch J, shunt regulator K and contacts m of the rotary switch M to the supply mains P. The mains G are adapted to be connected together through a brake resistance S when the contacts n , n , of the rotary switch N are connected together. The function of the resistance S when connected across the mains G is to form a circuit in which the kinetic energy stored up in the armatures of the working motor and the generator H, after the field of the latter has been deenergized, is used up as heat generated by the current in this circuit. The rotary switches M, N and a disk O are con-

nected together by the one shaft, which shaft is adapted to be driven at a suitable speed by any suitable form of friction drive, say by means of a friction clutch driven mechanically by the armature of the feed generator H. The shaft m^2 shown in Fig. 3 is connected by the gear m^3 to the switches M, N and O and it is driven by a friction clutch comprising a disk m^4 keyed on the shaft, a disk m^5 feathered on the shaft and pressed toward m^4 by a spring m^6 abutting against a stop m^7 , and a toothed disk m^8 located between m^4 and m^5 and driven by a chain m^9 from the wheel h^1 on the shaft h^2 connected to the armature of H by gear h^3 . The disk O is provided with a notch o^1 and the trip coil o^2 is provided with a detent plunger o^3 , the arrangement being such that the plunger o^3 normally engages in the notch and holds the rotary switches M and N stationary in the position shown in the drawings; the portion m^1 of the switch M and the portion n^1 of the switch N are of conducting material, so that in the stationary position the contacts m , m , are disconnected, while the contacts n , n , are connected. The switch T is adapted, when closed, to connect the trip coil o^2 across the supply mains P. The switch T is momentarily closed when the pawl t^1 (see Fig. 1) carried by the bar t^2 is moved from left to right by any suitable and adjustable tappet motion on the reciprocating parts. The switch T is provided with a spring t^3 which normally holds the switch open.

It will be seen that if, just prior to a cutting stroke, the switch T is closed, the trip coil o^2 is momentarily energized, and the plunger detent o^3 is raised clear of the notch, whereupon the frictional drive will cause the rotation of the rotary switches M and N. The first effect will be to open the circuit of the brake coil S; next, to energize the shunt winding s of the feed generator H, whereupon the motor C will begin to rotate, since the constantly running armature of H will now generate. The motor C and the feed screw to which it is attached will continue moving until the switches M and N have made one complete rotation, and return to the position shown in the drawings, when the shunt coil H_s is disconnected from the mains and the brake resistance S connected across the armature of the feed generator H and motor C, thus bringing the latter instantly to rest. The rotary switches will be maintained in this position by the plunger detent o^3 engaging in the notch o^1 . The amount of movement imparted to the motor C while the rotary switches make one turn, may be regulated by regulating the strength of the current in the field winding h_s by means of the regulator K.

It is necessary to be able to rotate the screw which is giving the feed—and of

- course the motor operating it—in either direction; this is accomplished in the arrangement illustrated by means of the reversing switch J which reverses the field of the generator, and of course causes the motor coupled to it to reverse its direction of rotation. The switch J is operated by hand by the attendant as required. It will be seen that while the motor A is operated so as to cause the reciprocation of the tool, the motor C is operated so as to give the tool the desired feed at the end of each stroke. Should it be desired to use the planer so as to reciprocate the tool vertically and to feed the 10 cut horizontally, it is only necessary to throw over the switch E so that the blades e^5 and e^6 now connect the motor A to the mains G and the blades e^3 and e^8 connect the motor C to the mains F.
- 15 The mains F are connected to the armature of a generator Q driven by a motor q ; q^1 is the motor field winding connected across the mains P. Q^1 is the generator field winding adapted 20 to be connected by the two way reversing switch R directly across the mains P (when the switch R is in the position shown in full lines) so that the current flows from one of the mains P to the other through contact r^1 , 25 blade r^2 , contact r^3 , conductor r^4 , field winding Q^1 , conductor r^6 , contact r^8 , blade r^7 and contact r^8 . When the switch R is moved to the position shown in dotted lines the field winding Q^1 is connected across the mains P 30 in series with the resistance Q^2 in which case the current flows in the opposite direction, viz:—through r^1 , r^2 , conductor r^9 , resistance Q^2 , field winding Q^1 , conductor r^4 , blade r^7 and contact r^8 . Thus when the 35 switch R is moved from one position to the other the direction of the current in the mains F is reversed and its magnitude altered. The switch R is operated by a tappet lever W and rod w^1 and the tappet lever is 40 actuated by the reciprocating part of the tool 45 by a tappet w^3 on the rod w^4 connected to said reciprocating part.
- The reversing switch R is known and forms no part of the present invention.
- The arrangement is very compact, and obviates the use of the cumbersome gearing which is necessary when one motor has to be employed alternatively to drive the horizontal or the vertical reciprocating gear. Moreover, according to the present invention, 50 only two motors are necessary to give the alternatively, horizontal and vertical movement and to provide electrical means for controlling the feed.
- Having now fully described my invention, 55 I declare that what I claim and desire to secure by Letters Patent is:—
- The improved apparatus for electrically operating and controlling planing and the like machines in which the tool is adapted 60 to be moved or reciprocated in either of two directions by separate operating means, which comprises two motors geared respectively to the said operating means; an electrical control gear actuated by the reciprocating part and adapted when connected to a motor to reverse and control its rotation 65 so that it reciprocates the tool; a second electrical control gear actuated by the reciprocating part and adapted when connected to 70 a motor to impart to the latter, between the cutting strokes, a limited angular movement; and change-over switches adapted to connect the two motors respectively to the two control gears in alternative manner; substantially as described.
- In testimony whereof I affix my signature in presence of two witnesses.

ARTHUR PEMBERTON WOOD.
